UNITED STATES PATENT OFFICE.

FRANZ MILLER, OF MILAN, ITALY.

ENGINE.

1,177,126.

Specification of Letters Patent. Patented Mar. 28, 1916.

Application filed August 23, 1915. Serial No. 46,922.

To all whom it may concern:

Be it known that I, FRANZ MILLER, a subject of the King of Italy, residing at Milan, Italy, have invented certain new and useful 5 Improvements in Engines, of which the following is a specification.

This invention relates to engines in which the transmission of the reciprocation of pistons into rotary motion of the driving shaft 10 is obtained by means of one or more undulated or cam guides or grooves on which the pistons act, and has for its object a type of engine comprising two or more independent pistons, which have different strokes so that 15 the expansion of the fluid may be fully utilized in the case the engine is operated by fluid under pressure.

One construction of engine according to this invention is shown in the annexed drawing, said engine comprising one or more 20 sets of coaxial and annular cylinders.

As shown in said drawing, the annular cylinders are formed by an outer wall 1 and an inner pipe 2 in which the driving shaft 25 3 is mounted. The wall 4 separates the chambers of cylinders 5 and 5' from each other, and said cylinders are further closed at their ends by the front walls 6, 6'. In said cylinders 5, 5', the independent pistons 30 7 and 7' are mounted, which are connected by means of rods 8, 8' passing through walls 6 and 4, with rings 9, 9' each comprising a set of rollers 10, 10' respectively. Said rollers are engaged in undulated or cam 35 grooves (one for each set of rollers) provided in the sleeve 11 solid with the driving shaft 3.

The base of the engine is provided with rectilinear guides 12, 12' on which bear rollers 13, 13', pivoted on the rings 9, 9', so that these rings may travel longitudinally but are prevented from rotating.

The pistons 7 and 7' being independent from each other may be caused to make 45 strokes having different lengths by giving different heights to the undulations of the cam grooves of sleeve 11 engaged by rollers 10 and 10'. In this case the expansion of the driving fluid may be fully utilized by 50 directing said fluid in cylinder 5' after it has acted in cylinder 5 owing to the fact that the required ratio between the volumes of cylinders 5 and 5' may be obtained by giving a longer stroke to the piston 7' so 55 that it is not required to increase exceedingly the diameter of the corresponding cylinder.

The pistons being independent from each other, it is also possible to eliminate the dead centers in the operation of the engine by angularly displacing the cam grooves with 60 regard to each other or by angularly displacing the line of thrust of rollers 10, 10' engaging the same cam groove or different cam grooves having the same angular position. In this case, by way of example, when 65 the high pressure piston has reached the end of its stroke, the low pressure piston is still actuating the driving shaft, a further portion of stroke having to be made by it.

In the case the strokes made by the pistons 70 are different from each other, and the member providing the cam grooves or guides for the rollers is in form of a cylindrical sleeve, it is advisable to provide the groove or guide having the smaller wave height in the inner 75 wall of the sleeve while the groove or guide having the larger wave height is made in the outer surface, this latter being not confined by the spokes or disk connecting said sleeve with the driving shaft. This is the 80 case shown in the drawing, the engine illustrated being further balanced owing to the fact that the pistons reciprocating in the cylinders are symmetrical to that 5 and 5' and operate cam grooves each of which is 85 symmetrical to the corresponding one.

By means of the described arrangement an engine is obtained in which the driving fluid, as steam, is caused to operate pistons making strokes of different length, in order 90 to effect the multiple expansion, the pistons exerting their thrust on cam grooves of the member solid with the driving shaft along lines angularly displaced with regard to each other in order to eliminate the dead 95 centers.

What I claim as my invention and desire to secure by U. S. Letters Patent is:—

1. In an engine having two or more coaxial cylinders and in which the transmission of reciprocation of the pistons into rotary motion of the shaft is effected by means of undulated members, an independent piston in each cylinder, a member solid with the driving shaft provided with independent undulated members having different wave heights and means for transmitting the thrust of each piston to one of said undulated members. 100

2. In an engine having two or more coaxial cylinders and in which the transmission of reciprocation of the pistons into rotary motion of the shaft is effected by means of undulated members having different wave heights and means for transmitting the thrust of each piston to one of said undulated members. 110

- tary motion of the shaft is effected by means of unlulated members, an independent piston in each cylinder, a sleeve solid with the driving shaft provided with undulated members having a given wave height on its outer surface and a different height on the inner surface, and means for transmitting the thrust of each piston to one of said undulated members.
- 10 3. In an engine having two or more coaxial cylinders and in which the transmission of reciprocation of the pistons into rotary motion of the driving shaft is effected by means of undulated members, an independent piston in each cylinder, a sleeve solid with the driving shaft, undulated grooves having a given wave height in the outer surface of said sleeve, undulated grooves having different wave height in the inner surface of said sleeve, sets of rollers the rollers of each set being engaged in one of said grooves and pivoted on a ring, means for guiding the travel of said rings, and means for connecting each ring to the corresponding piston.
- 15 4. In an engine having two or more coaxial cylinders and in which the transformation of reciprocation of pistons into rotary motion of the shaft is effected by means of undulated members, an independent piston in each cylinder, a part solid with the driving shaft, undulated members having different wave height and angularly displaced with regard to each other in said part, and means for transmitting to each of said undulated members the thrust of each piston.
- 20 5. In an engine having two or more coaxial cylinders and in which the transformation of reciprocation of pistons into rotary motion of the driving shaft is effected by means of undulated members, an independent piston in each cylinder, a sleeve solid with the driving shaft, undulated grooves in the outer surface of the sleeve, undulated grooves in the inner surface of said sleeve having different undulation and angularly displaced with regard to the outer ones, sets of rollers the rollers of each set being engaged in one of said grooves and pivoted on a ring, means for guiding the travel of said rings, and means for connecting each ring to the corresponding piston.
- 25 6. In an engine having one or more pairs of coaxial cylinders and in which the transformation of reciprocation of pistons into rotary motion of the driving shaft is effected by means of undulated members, independent pistons each arranged opposite to another one, a part solid with the driving shaft, independent undulated members in said part, each symmetrical to another one, undulated members in said part each symmetrical to another one having different undulations and angularly displaced with regard to the first named undulated members and means for transmitting to each pair of symmetrical undulated members the thrust of two opposite pistons.
- 30 7. In testimony whereof I affix my signature 70 in presence of two witnesses.
- 35 8. FRANZ MILLER.
